ATTORNEY.

UNITED STATES PATENT OFFICE.

IVAN D. THORNBURGH, OF OAKLAND, CALIFORNIA, ASSIGNOR TO AMERICAN CAN COMPANY, OF SAN FRANCISCO, CALIFORNIA, A CORPORATION OF NEW JERSEY.

SANITARY-CAN END.

1,299,063.

Specification of Letters Patent.

Patented Apr. 1, 1919.

Application filed May 17, 1916. Serial No. 98,166.

To all whom it may concern:

Be it known that I, IVAN D. THORNBURGH, a citizen of the United States, residing at Oakland, in the county of Alameda and State of California, have invented certain new and useful Improvements in Sanitary-Can Ends, of which the following is a specification.

The present invention relates to a can end for the closure of cans of the so-called sanitary, or solderless, type, and constitutes an improvement on the can end closure for which United States Letters Patent No. 1,100,005 was granted to John M. Young on June 16, 1914.

It is well known in the art that the most successful form of packing for the seam of a can of this type is a ring liner, formed preferably of paper or other fibrous material, and loosely applied to the flange of the can end before said end is placed in position on the can. To prevent mutilation of the liner, especially in the event of dampness, it is required that the same be loose and free to move on the flange of the end. Therefore, in order to retain said liner within the groove of said flange during the necessary handling of the end, it has been customary to in-turn or curl the outer edge of the flange.

With some types of seam, however, and particularly that in which the seal is maintained by means of a separate ribbon or so-called sealing strip, crimped and clamped over the adjacent edges of the flanges of the can and the end, it is not practicable to curl the outer edge of the end flange. In such cases it is necessary to provide other means for loosely retaining the ring liner in position on the flange.

The object of the present invention, therefore, is to provide a can end of the straight flange type having means for loosely retaining a ring liner in position upon its flange, without interfering with the proper functions of the liner or the flange in their ultimate relation to the finished seam.

In order to comprehend the invention, reference should be had to the accompanying drawings, wherein—

Figure 1 is a plan view of the inner face of an unlined can end of my improved type.

Fig. 2 is a plan view of the ring liner designed to be applied to the flange of the can end.

Fig. 3 is a plan view of the inner face of the can end with the liner applied to the flange thereof.

Fig. 4 is a central transverse section showing the can end and the liner before being assembled.

Fig. 5 is a central transverse section of the can end with the liner applied to the flange thereof.

In the drawings, the reference numeral 1 designates a can end, here shown as having a straight, or non-curved peripheral flange 2, upon which rests, in freely movable relation, the ring liner 3. The inner bounding shoulder 4 of the flange 2 (which is usually a straight wall) is contracted or crimped, at the point 5 to provide an annular or circumferential groove 7, as shown clearly in Figs. 4 and 5 of the drawings, so that the diameter of said shoulder 4 at said point 5 is less than the diameter of said shoulder 4 at the point 6.

The inner diameter of the ring liner 3 is approximately equal to the outer diameter of the shoulder 4 at the point 5, and is less than the diameter of said shoulder 4 at the point 6. In applying the liner 3 to the flange 2 of the can end, therefore, said liner must be distorted, in order to pass over the greater diameter, at 6, of the shoulder 4. This may be done in any suitable mechanism and in any suitable manner, as, for example, by applying one side of the liner first, and then gradually forcing the remainder over the shoulder of the flange until the whole of the inner edge of the said liner is seated or rests within the annular groove 7. When the liner is entirely in position on the flange, as shown in Fig. 5 of the drawings, it is retained by the enlarged overhanging portion 6 of the shoulder 4, while being free to move upon the flange.

The object of providing means for loosely retaining the liner upon the flange of the can end is thus achieved without inturning or curling the edge of the flange 2.

Having thus described my invention, what I claim as new and desire to protect by Letters Patent is:—

1. In combination, a can end for the closure of sanitary cans having an outwardly projecting flange for the seaming thereof to a can body, said flange being bounded by a shoulder having a peripheral recess, said shoulder and flange providing an unob-

structed angular seat for the can top, and an inelastic ring liner held in said recess and adapted to lie upon said flange, the inner diameter of said liner being less than the 5 greatest diameter of said shoulder.

2. A can end for the hermetic closure of sanitary cans, the same being formed with a peripheral shoulder forming the resisting means for the seaming operation to enter 10 within the mouth of the can and with a flange extending outward from the upper part of said shoulder, said shoulder being formed with an inward peripheral recess, and a nonelastic thin fibrous ring liner

15 having an inner diameter less than the greatest diameter of said shoulder held in said recess by the outwardly extending lower part of said shoulder.

3. A can end for the hermetic closure of 20 sanitary cans, the same being formed with a peripheral shoulder to enter within the mouth of the can and with a flange extending outward from the upper part of said shoulder, said shoulder being formed with

25 an inward peripheral recess, and a paper ring liner having an inner diameter less than the greatest diameter of said shoulder held loosely and freely movable in said recess by the outwardly extending lower part 30 of said shoulder.

4. A can end for the hermetic closure of sanitary cans, the same being formed with a

peripheral shoulder to enter within the mouth of the can and with a flange extending outward from the upper part of said shoulder, said shoulder being formed with an inward peripheral recess, and an inelastic paper ring liner having an inner diameter less than the greatest diameter of said shoulder held in said recess by the outwardly extending lower part of said shoulder, the said flange being flat and leaving free the outer edge of the liner.

5. A can end for the hermetic closure of sanitary cans, the same being formed with a 45 peripheral shoulder to enter within the mouth of the can and with a flange extending outward from the upper part of said shoulder, said shoulder being formed on an inward and upward incline to leave a narrow and rounded lower edge and a recess above said edge, and an inelastic paper ring liner held on the inclined part of said shoulder above said edge, its internal diameter being slightly less than the greatest diameter of said edge.

In testimony whereof I have signed my name to this specification in the presence of two subscribing witnesses.

IVAN D. THORNBURGH.
